UNITED STATES PATENT OFFICE.

GEORGE ROBBINS, OF MINNEAPOLIS, MINNESOTA.

DESIGN FOR A COAT.

Application filed November 7, 1925. Serial No. 15,379. Term of patent 3½ years.

To all whom it may concern:

Be it known that I, GEORGE ROBBINS, a citizen of the United States, residing at Minneapolis, in the county of Hennepin and State of Minnesota, have invented a new, original, and ornamental Design for a Coat, of which the following is a specification, reference being had to the accompanying drawings, forming a part thereof.

Referring to the drawings:

Fig. 1 is a view in front elevation of the coat with the collar turned up;

Fig. 2 is a view in rear elevation of the coat with the collar turned up.

I claim:

The ornamental design for a coat, as shown.

GEORGE ROBBINS.
